UNITED STATES PATENT OFFICE

155,866

DESIGN FOR A SUIT

J. Leah Asteroff, New York, N. Y.

Application February 25, 1949, Serial No. 1,088

Term of patent 3½ years

(Cl. D3—4)

To all whom it may concern:

Be it known, that I, J. Leah Asteroff, a citizen of the United States, residing in New York city, in the county of New York and State of New York, have invented a new, original, and ornamental Design for a Suit, of which the following is a specification, reference being had to the accompanying drawing, forming part thereof.

Fig. 1 is a front view of a suit, showing my design, and

Fig. 2 is the rear view thereof.

I claim:

The ornamental design for a suit, substantially as shown.

J. LEAH ASTEROFF.
